UNITED STATES PATENT OFFICE.

WILLIAM CRUTCHLOW, OF PATERSON, NEW JERSEY.

DOBBY.

SPECIFICATION forming part of Letters Patent No. 745,041, dated November 24, 1903.

Application filed June 26, 1903. Serial No. 163,174. (No model.)

To all whom it may concern:

Be it known that I, WILLIAM CRUTCHLOW, a citizen of the United States, residing in Paterson, in the county of Passaic and State of New Jersey, have invented certain new and useful Improvements in Dobbies; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates to shedding mechanisms for looms; and it has for its object to so construct a shedding mechanism of the kind commonly known as the "dobby" type that by the use of simple expedients highly-variegated patterns may be worked out in the goods to be woven.

My invention is found fully illustrated in the accompanying drawings, wherein—

Figure 1 is a view in side elevation of the end portion of a loom, showing my improved dobby in position thereon. Fig. 2 is a view substantially similar to Fig. 1 except that the parts are viewed from the opposite standpoint. Fig. 3 is a view of the dobby looking in the direction of the arrow in either Figs. 1 or 2, and Fig. 4 illustrates a modification of the invention.

On the loom-frame *a* is secured in any desired manner the dobby *b*. *c* designates the jacks, fulcrumed in the dobby-frame at *d* and pivoted to their jack-levers *e* in the usual manner. Said jack-levers are adapted to be operatively connected with the knives *f* through the medium of upper and lower hooks *g* *g'*, each corresponding upper and lower hook being connected by a rod *h*, so as to work vertically together when the rod is actuated by a corresponding one of a set of levers *i*. The knives are reciprocated in the usual manner from rocking levers *j*, to which they are connected by links *k*.

The indicator mechanism, which consists of the usual cylinder *l* and endless set of pattern-cards *m*, is carried by a bell-crank lever *n*, fulcrumed on a shaft *o* in the dobby-frame and actuated by a spring *p*, which connects it with the frame of the loom, so that the in-

dicator mechanism normally tends to lower. It is elevated against the tension of the spring from a cam *q* on one of the rotary shafts *r* of the loom, the lever *n* carrying a roller *s*, which engages the cam. The cylinder carries the usual ratchet *t*, with which at each movement of the indicator mechanism a spring-actuated pawl *u* coacts to turn the cylinder. The cylinder also carries the usual polygonal block *v*, engaged by a spring-actuated lever *w* for intermittently holding the cylinder against turning.

Each pattern-card has a plurality of rows *x* of pins or other projections in relatively varied arrangement. The needles *y*, which are actuated from these pins and in turn actuate the levers *i*, are arranged to slide vertically in the horizontal portion of a U-shaped frame *z*, which I term a "switch" and which is suspended from pivots *1* on supporting-arms *2*, extending from the dobby-frame. According as this switch is shifted so as to bring the needles in alignment with the one or the other of the rows of pins *x* on the pattern-cards so different combinations of the levers *i* are selected and actuated. The shifting of switch *z* is effected by the following mechanism:

Switch *z* is normally pulled outwardly by a spring *3*, connecting it with a fixed arm *4*. Its limit of movement under the pull of the spring is a stop *5* on the dobby-frame. When the switch is against the stop, the needles *y* will be opposed to one of the end rows of pins *x* on that card which is in operative position relatively to the needles. *6* is an actuating device for the switch in the form of a hook having its hooked portion stepped, as at *7*, each step corresponding to one of the other rows of pins on each card. This hook is pivotally connected to the upper end of a lever *8*, fulcrumed on the shaft *o*, and it is also pivotally connected to the upper end of a certain link *9*. Lever *8* is continually oscillated from a face-plate *10* through the medium of a link *11*, the face-plate being carried upon the upper end of a shaft *12*, which is journaled in a part of the dobby-frame and carries at its lower end a bevel-gear *13*, engaging a bevel-gear *14* on a shaft *15*, which carries a gear *16*, meshing with a pinion *17* on the shaft *r*.

As lever 8 oscillates it causes the hook 6 to reciprocate, and according as this hook is raised or lowered to any given extent so the one or the other of the steps 7 thereof is brought against the switch to move the same against the tension of its spring. The raising and lowering of hook 6 is accomplished through link 9 from a lever 18, which is fulcrumed in a suitable support 19 and is connected with a lever 20 by means of a suitable elastic connection in the form of a rod 21, pivoted to the lever 20, another rod, 22, pivoted to the lever 18 and having a sliding engagement with the rod 21, and a spring 23, normally acting on the rods, so as to extend the connection which they constitute. Lever 20 is controlled from the balls or rolls 24 on a pattern-chain 25 of a suitable indicator mechanism 26.

In the modified form of the switch mechanism the switch 27 is guided in a slot 28 in the dobby-frame and is normally pulled outwardly by a spring 29. It is actuated from the hook 6 in the same manner that that already described is actuated. Since, however, the switch in this instance slides, it becomes necessary to prevent its actuating means (the hook, which engages it only at one end) from disturbing its parallelism with reference to the pins *x*, and this is accomplished by connecting it by links 30 with cranks 31 on a rock-shaft 32, journaled in the dobby-frame.

33 is a spring for insuring contact between lever 20 and the rolls 24.

Operation: It will be understood that levers *j* are rocked and shaft *r* rotated continuously, so that the jacks, which are selected from the indicator mechanism, are moved on their fulcrums to shift the harness and so that the indicator mechanism is moved not only to select the jacks to be moved, but so as to be caused to advance, and thus present a new card to the needles *y* at each movement.

From pinion 17 lever 8 is kept also in continuous motion. Whenever the indicator mechanism is elevated, one of its rows of pins, depending upon the position of the switch *z*, engages the needles *y*, which elevate the levers *z*, corresponding thereto, whereby the hooks *g g'*, controlling the jacks to be operated, are lowered into the position where they will be engaged by the knives. While the warps forming the shed are in any given arrangement the changing of the position of switch *z* incident to the formation of a new shed begins, lever 8 having meantime forced hook 6 outwardly and begun its reverse motion, and the indicator mechanism 26 having, through the mechanism connecting lever 20 with hook 6, disposed hook 6 where a given one of its steps will engage the switch. As the hook recedes it pulls the switch with it (provided, of course, the hook engages the switch at all) and at its rearward limit of motion will hold the needles at the point where when the new card is presented the predeter-

mined row of pins will engage needles *y*. Just as the switch reaches its extreme rearward position roller *s* rides up on the highest portion of cam *q* and so forces the pattern-card presented against the needles, elevating them and levers *i*. Thereupon roller *s* begins to run down on cam *q*, permitting the indicator mechanism to recede from the needles, while lever 8 advances, thus causing hook 6 to permit the switch to return to the stop. From this point on the operation is simply a repetition of that described.

The indicator mechanism 26 I preferably use to perform the double function of controlling the position of hook 6 and controlling levers 34, from which the boxes of the loom are called. As the calling of the boxes of a loom precedes the forming of the shed, it becomes necessary in the present case, where the same indicator mechanism works both the levers 20 and the levers 34, to make some portion of the connecting mechanism between lever 20 and hook 6 elastic, so that whenever lever 20 acts to pull down on hook 6 while said hook is still engaged with the switch there will be a yielding effect produced in said connecting mechanism. It is for this reason that the flexible connection between levers 18 and 20, afforded by the parts 21, 22, and 23, is provided.

It should be understood that while the same general indicator mechanism 26 controls both the boxes and the forming of the sheds still the balls or rolls 24 are divided into two sets, one actuating levers 20 and the other levers 34. The controlling of the boxes and the forming of the sheds from the same indicator mechanism has been heretofore proposed; but the medium for accomplishing this was one of the levers 34. Hence because the variety of positions of this lever is so limited the number of different sheds capable of being formed is limited. By dividing the balls or rolls into two sets one of them can be made so that in combination with lever 20 any variety of sheds may be produced, while the other set does the more limited work of actuating the boxes.

Having thus fully described my invention, what I claim as new, and desire to secure by Letters Patent, is—

1. The combination of a support, jacks fulcrumed in said support, knives, hooks adapted to be actuated by the knives, means for connecting the hooks and the jacks, movable hook-controlling devices, needles controlling said devices, an indicator mechanism coactive with the needles, a switch adapted to move the needles with reference to the indicator mechanism, a graduated part engageable with the switch and adapted to shift the same, means for imparting a regular movement to said graduated part, and means for adjusting said graduated part relatively to the switch, substantially as described.

2. The combination of a support, jacks fulcrumed in said support, knives, hooks adapt-

ed to be actuated by the knives, means for connecting the hooks and the jacks, movable hook-controlling devices, needles controlling said devices, an indicator mechanism coactive with the needles, a switch adapted to move the needles with reference to the indicator mechanism, a stepped part engageable with the switch and adapted to shift the same, means for imparting a regular movement to said stepped part, and means for adjusting said stepped part relatively to the switch, substantially as described.

3. The combination of a support, jacks fulcrumed in said support, knives, hooks adapted to be actuated by the knives, means for connecting the hooks and the jacks, movable hook-controlling devices, needles controlling said devices, an indicator mechanism coactive with the needles, a switch carrying the needles and movable with reference to the indicator mechanism, a stop, elastic means for normally maintaining said switch against the stop, a graduated part engageable with the switch and adapted to move the same away from the stop, means for imparting a regular movement to the graduated part, and means for adjusting said graduated part relatively to the switch, substantially as described.

30 4. The combination of a support, jacks fulcrumed in said support, knives, hooks adapted to be actuated by the knives, means for connecting the hooks and the jacks, movable hook-controlling devices, needles controlling said devices, an indicator mechanism coactive with the needles, a switch carrying the needles and movable with reference to the indicator mechanism, a graduated part engageable with the switch, adapted to shift the same, and movable both in the same direction as the switch and substantially at right angles thereto, means for imparting a regular movement to said part in the direction of movement of the switch, and means

for moving said part substantially at right angles to the direction of movement of the switch, substantially as described.

5. The combination of a support, jacks fulcrumed in said support, knives, hooks adapted to be actuated by the knives, means for connecting the hooks and the jacks, movable hook-controlling devices, needles controlling said devices, an indicator mechanism coactive with the needles, a switch carrying the needles and movable with reference to the indicator mechanism, a graduated part engageable with the switch and adapted to shift the same, means for imparting a regular movement to said graduated part, another indicator mechanism, and operative connecting means between said last-named indicator mechanism and the graduated part, said last-named indicator mechanism being adapted to adjust the graduated part relatively to the switch, substantially as described.

6. The combination of a support, the hooks, means whereby to connect the hooks with the harness, movable hook-controlling devices, knives, needles controlling said devices, an indicator mechanism coactive with the needles, a switch adapted to move the needles with reference to the indicator mechanism, a regularly-moving part for controlling the position of the switch, said switch and said controlling part having engaging portions one of which is graduated and means for moving one of them to bring the engaging portion of the one into engagement with the other, arbitrarily, at any of the points on the graduated engaging portion thereof, substantially as described.

In testimony that I claim the foregoing I have hereunto set my hand this 24th day of June, 1903.

WILLIAM CRUTCHLOW.
